SAFETY DEVICE

Elmer Olson, Ferndale, and Stanley M. Udale,
Detroit, Mich., assignors to George M. Holley
and Earl Holley

Application October 16, 1944, Serial No. 558,918

2 Claims. (Cl. 123—119)

1

The object of this invention is to protect a marine engine from excessive speed. When a boat is traveling fast in a rough sea, rough enough to raise the propeller out of the water, the engine which drives the boat has a tendency to race, and excessive engine speeds are attained. The specific object of this invention is to temporarily close the throttle and to simultaneously interrupt the fuel flow.

Figure 1 shows the preferred form of our invention.

Figure 2 shows a simpler alternative construction.

Figure 3 shows a cross-sectional elevation through plane 33 of Figure 1.

Description—Figure 1

In the figure, 10 is the air entrance, 29 is the fuel nozzle, 30—31 are the discharge outlets for the fuel nozzle between the throttles 13 and 14. The air-fuel mixture is compressed in an engine driven supercharger contained in housing 70. 68 is the fuel chamber controlled by the diaphragms 24 and 25. The fuel inlet 110 admits fuel past the fuel needles 111 and 112 into the chamber 68. These fuel needle valves 111 and 112 are connected to the diaphragm 25—24 in a well-known manner. The pressure on the diaphragm is controlled by the air chambers 26 and 27, which are connected by the air passage 81. The chamber 86 is vented to the atmosphere through the opening 91. The fuel outlet 11 is provided with a restriction 28, which is controlled by a needle valve 12, which in its turn is controlled by a lever 21, the movement of which is controlled by a roller 22 riding on a cam 19. A spring 20 keeps the roller 22 in engagement with the cam 19.

The throttles 13 and 14 are controlled by intermeshing gears 16 and 17 and a gear 15, the axis of which carries the cam 19 and is operated by lever 92. The lever 92 is connected to a piston 93, which slides in a cylinder 94, in which is a spring 95; cylinder 94 carries a stop 96 to limit the outward movement of piston 93. A manually-operated throttle lever 109 is connected to the left-hand end of the rod 108, which projects from the cylinder 94. The pressure inside the cylinder 94 is the pressure inside the chambers 26 and 27 because a flexible rubber tube 97 connects the inside of the cylinder 94 with the chambers 26 and 27. A passage 98 connects chambers 26 and 27 and the cylinder 94 with a chamber 99, which communicates through an opening 100 with the throat of the variable venturi formed by throttles 13 and 14. An armature

2

101 carrying a valve 102 which is attracted by an electric solenoid 103 whenever the differential switch 86 admits the current from a battery 87 through a conductor 104. The valve 102 is arranged to control passage 98.

A centrifugal governor 85 through a lever 105 operates the differential switch 86, the governor being driven from the engine by the shaft 84. The differential switch is adjusted to complete the circuit at 2800 revolutions per minute and to open the circuit at 2500 revolutions per minute. Figure 3 shows how the differential switch 86 operates.

Operation—Figure 1

15 When the speed exceeds a predetermined speed, such as 2800 revolutions per minute, the governor 85 operates the differential switch 86 energizing the solenoid 103 which raises the armature 101 and thus the valve 102 and to admit the suction effect in the chamber 99 into the chambers 26—27 and into the inside of the cylinder 94. The throttles 13—14 are thus closed at the same time the suction in the chambers 26—27 prevents the fuel flowing along the passage 11. When the speed falls to 2500 revolutions per minute, the differential switch 86 is opened, the armature 101 being released by the solenoid 103 and the suction in the chambers 26 and 27 is destroyed. The suction in the cylinder 97 is also destroyed so that the spring 95 reopens the throttles and the atmospheric air pressure admitted past opening 91 into the chambers 26 and 27 restores the normal flow of fuel.

Description—Figure 2

Figure 2 shows an alternative construction in which the supercharger pressure in housing 70 in Figure 2 is connected through a pipe 71 to a cylinder 72, in which a piston 114 is mounted loaded by a spring 73. A passage 71 connects the chamber 74 above the piston with the chambers 26—27. The piston carries a valve 102' which when held down by the spring 73 closes the passage 98, which passage communicates with the variable venturi through port 100 in throttle 13.

Operation—Figure 2

50 The valve 102', when open, admits suction from the passage 98 to the flexible pipe 97 when the supercharger pressure exceeds the pressure corresponding to the spring 73. When the supercharger pressure 70' exceeds the value corresponding to the compression spring 73, the valve 102' rises and the application of suction to the cylinder 84 causes the throttle lever 92 to move

clockwise, closing the throttles 13 and 14. At the same time, suction applied to the chambers 26 and 27 causes the diaphragms 24 and 25 to shut off the supply of fuel. Meanwhile the suction in the chambers 26 and 27 is transmitted through the passage 77 to the chamber 74 where it assists the compression pressure in cylinder 72 in compressing the spring 73. Hence, the valve 102' remains open until the revolutions per minute of the engine has fallen to the desired number of revolutions per minute, but before the engine stalls. The compression from the super-
charger then falls permitting the valve 102' to descend and the engine is restarted.

Without the passage 77, the valve 102' would 18 hunt. The engine should run slowly long enough to permit the operator to close the throttle if the propeller had been lost. If the propeller had merely raced due to it being raised free of the water by a wave, then it would automatically pick up speed without any attention from the operator. The pipe 98 is connected to the throat of the venturi 13-30 through the opening 100, therefore, no pressure above atmospheric pressure can ever exist in the pipe 98.

What we claim is:

1. A safety device for an internal combustion engine having an engine driven supercharger, an air inlet passage leading thereto, a throttle valve therein, an engine suction pipe connected to said inlet passage on the engine side of said throttle, a control valve in said suction pipe, means responsive to the supercharger pressure for opening said control valve when the supercharger pressure exceeds a predetermined value, means responsive to the engine suction thus controlled

4
for holding said valve open and for shutting off the fuel supply until the supercharger pressure falls a predetermined number of pounds per square inch.

5 2. A safety device for an internal combustion engine having an engine driven supercharger, an air inlet passage leading thereto, a throttle valve therein, an engine suction pipe connected to said inlet passage on the engine side of said throttle, 10 a control valve in said suction pipe, means responsive to the supercharger pressure for opening said control valve when the supercharger pressure exceeds a predetermined value, means responsive to the engine suction thus controlled for maintaining the valve in the open position and for holding the throttle closed until the supercharger pressure has fallen a predetermined number of pounds per square inch below the pressure at which said control valve opens.
